UNITED STATES PATENT OFFICE.

FRANKLIN M. FRAZIER, OF PLACERVILLE, COLORADO.

KNITTING NEEDLE.

Application filed January 26, 1927. Serial No. 163,582.

My invention relates to improvements in knitting needles and the use thereof, and has for one object to provide a conventional latch needle in connection with a movable jacket adapted to coact with said latch needle in the manner hereinafter described.

Another object of my invention is to provide a means on said jacket adapted to insure the opening of the latch of said latch 10 needle thereby preventing the dropping of stitches which result when the latch closes the hook of the latch needle at the time when the yarn is being fed thereto.

Another object is to provide, by the coaction of said jacket with said latch needle, 15 means for dropping stitches from one knitting needle to another, means being provided on said jackets for this purpose.

Another object is to provide such knitting 20 needles adapted to coact in pairs, the needles of each of said pairs being in opposed spaced relation, means being provided on the jackets whereby said coaction may take place.

With the above and other objects in view 25 my invention consists in the combination and arrangement of parts hereinafter described and claimed, and more particularly illustrated in the accompanying drawings, in which:

Figure 1 is a vertical sectional view of sufficient of a knitting machine to illustrate 30 my present invention, the knitting needles being shown in their idling knitting positions.

Figure 2 is a view of the knitting needles as shown in Figure 1, showing the knitting 35 needles in the first operation of knitting, to receive the yarn.

Figure 3 is a view similar to Figure 2, but 40 showing the second operation, of drawing the yarn thru the previous stitch.

Figure 4 is a view similar to Figure 2, but 45 showing the third operation, wherein the new loop is formed.

Figure 5 is a fragmentary view of a portion of Figure 2, showing the latch being 50 opened to receive the yarn.

Figure 6 is a view similar to Figure 2, but 55 showing the knitting needles in the first operation of dropping a stitch.

Figure 7 is a view similar to Figure 6, 60 showing the second operation of dropping a stitch.

Figure 8 is a view similar to Figure 5,

showing the knitting needle retracted into 55 the straight bed.

Figure 9 is an end view of Figure 13.

Figure 10 is a sectional view along the line 10—10 of Figure 11.

Figure 11 is a plan view of Figure 13. 60

Figure 12 is a fragmentary plan view of a portion of Figure 7, showing the relation of the pair of coacting needles.

Figure 13 is a fragmentary view of one of the knitting needles of Figure 1, showing the 65 latch needle retracted into the jacket and the latch closed.

Figure 14 is a plan view of the knitting needle removed from the straight bed.

Referring now more particularly to the 70 drawings, I show a latch needle A, coacting with a jacket B; the numeral 10 refers to a straight bed or needle carrying member of a knitting machine, and 11 represents a part of a cam plate or other cam member of the 75 machine. Two such straight beds with their cam plates are shown in opposed relation, the straight beds being disposed right angularly with each other.

The straight beds have lands 12' forming 80 jacket grooves 12, and each jacket B comprises a body portion 13 adapted to slidably engage said jacket grooves, a butt 14 adapted to be acted upon by a projecting cam 15 and a retracting cam 16 on the cam plate 11, 85 whereby the longitudinal reciprocation of the jacket in its respective groove is effected.

Each jacket body portion 13 has a latch 90 needle groove 17 and each latch needle A comprises a hooked member 18 adapted to slidably engage said needle groove, a butt 19 positioned medially said hooked member, and a butt 20 adapted to be acted upon by a projecting cam 21 and a retracting cam 22 on the cam plate 11, whereby the longitudinal reciprocation of the latch needle in the jacket is effected. Said hooked member 18 has a hook 23 at its outer end and a latch 24 adapted to coact with the hook in the conventional manner. 95

The jacket body portion 13 has a cover 25 provided with a slot 26 adapted to have the butt 19 slidably engaged therein, for the purpose of preventing the rotation of the latch needle A in the jacket B. The said 100 body portion 13 is formed at its outer end with a nose comprising upper and lower converging faces, the intersection of the up-

per face 27 with the lower face 28 coinciding with the bottom of the latch needle groove 17. In the embodiment illustrated the upper face 27 is sloping, and the lower face 28 is vertical and has a vertically extending groove 31 for the purpose of permitting the coaction of opposing pairs of knitting needles as hereinafter described. A portion of the needle groove 17 is closed over to provide a guide 29 adapted to slidably engage the inner end of said hooked member 18.

In the position shown in Figure 2, the jackets B are flush with the straight bed 10, and the latch needles A are projected outwardly the jackets B to receive the yarn 31' from the yarn feeder (not shown). The latches 24 are open. It is intended that the needles shall be so positioned in the knitting machine that the needles A, A', and their jackets B, B' will be disposed in opposing paired relation, but so as to permit the hook 23 of one needle to project past the hook 23' of the other needle. For the purpose of illustration the previous stitch is shown on the needles transversely the straight beds, but it is understood that in normal operation the stitches will extend along and between the straight beds from one needle to the other.

In Figure 3 the jackets B, B' are shown retracted into the straight bed and the needles A, A' are being drawn through the previous stitch. In Figure 4 the jackets B, B' and the needles A, A' together are retracted into the straight bed and the new loop drawn through the previous stitch. In Figure 5, the needles A, A' are shown partly projected outwardly the jackets B, B' and the latch partly opened, and the jackets B, B' are projected flush with the straight bed. In the next operation the needles A, A' are projected outwardly the jackets B, B', to the position shown in Figure 1, from whence the sequence of operations described is repeated.

When it is desired to drop a stitch as at 32, the jacket B of the needle from which the stitch is to be dropped is projected outwardly the straight bed 10; at the same time the succeeding needle A' is projected outwardly its jacket B' so as to cause the said needle A' to pass through the stitch 32 and to have its hook 23' engage the groove 31 of the jacket B of the needle from which the stitch is to be dropped. Coincidently the needle A is projected outwardly its jacket B so as to cause the stitch 32 to slip below the latch 24, as shown in Figure 6. In Figure 7 is shown the latch needle A retracted into its jacket B whereby the stitch is disengaged from the hook 23 by the upper face 27 of the nose of the jacket B, whereupon the stitch may be dropped onto the hooked member 18' of the succeeding needle A'. In

Figure 8 is shown the jacket B and the latch needle A together retracted into the straight bed so as to be flush therewith and well out of the way of the needles that are in operation.

In Figure 12 is shown how the hook 23' of the latch needle A' is adapted to extend into engagement with the slot 31 of the jacket B of the opposing needle of the pair, so that the stitch 32 in slipping off the face 27 of the nose of the jacket B is adapted to be engaged by the hooked member 18' of the latch needle A'.

While I have shown and described my invention in connection with a straight machine it is understood that I may employ the same in connection with other than straight machines, and that I may vary the method of constructing and assembling the elements of my invention in minor details, not departing from the spirit of my invention, so as best to construct a practical device for the purpose intended, as defined in the appended claims.

I claim:

1. The combination of a knitting machine needle comprising a latch needle having a pivoted latch, with a jacket mounted upon but having a movement independently of said latch needle, the outer end of said jacket being formed with converging upper and lower faces; the latch needle being adapted to project through the upper face; a cover provided for said jacket; said cover having a slot extending in the direction of said movement; and a butt on the latch needle adapted to engage said slot; said jacket being formed with a bearing adapted to slidably engage said latch needle, said jacket and latch needle being susceptible of movement one in respect to the other in the direction of travel of the needle for transferring the yarn from the needle to the jacket.

2. The combination, in a knitting machine, of knitting needles adapted to coact in opposing pairs, each of said knitting needles comprising a latch needle having a hook adapted to coact with a pivoted latch, a jacket mounted upon but having a movement independently of said latch needle, said jacket having a slot extending in the direction of said movement, the end of said jacket corresponding to said hook being formed with converging upper and lower faces intersecting at the bottom of said slot, the latch needle being adapted to project through the upper of said faces; the said jacket also having a groove formed in the lower of said faces whereby the hook of one needle of a pair may be adapted to coact with the jacket of the other needle.

3. The combination, in a knitting machine having opposing needle beds, of needles slidably mounted in the beds and adapted

to coat in opposing pairs, jackets loosely mounted in one of the beds adapted to slidably engage the respective needles therein, each of the jackets having its outer end 5 formed with upper and lower converging faces, means for retracting the needle of each jacket thereinto for casting the yarn from said needle to the upper face of the jacket, and means for projecting the opposing needle into contact with the lower 10 face of said jacket for transferring the yarn from said jacket to said second mentioned needle, said means being operative prior to casting the yarn onto the jacket.

4. The combination in a knitting machine 15 having opposing needle beds, of latch needles adapted to coat in opposing pairs, and a jacket mounted in one of the needle beds coacting with a needle in its respective bed to cast the yarn therefrom, and means 20 for contacting said jacket with the hook of the opposing needle for reception of the yarn from said jacket, said contact being effected prior to casting the yarn onto the 25 jacket.

In testimony whereof I affix my signature.

FRANKLIN M. FRAZIER.
